METAL DRAWING APPARATUS

Walter F. Schulz, Youngstown, Ohio, assignor of
one-half to Julius Kahn, Youngstown, Ohio

Application August 16, 1933, Serial No. 685,479

24 Claims. (CL 80—36)

The object of the present invention is to provide a simple, practical apparatus for drawing wire or other elongated products with speed and with the requirement of relatively small power.

Under the present practice in general use, fixed dies are employed that are made from diamonds for the extremely light wires, and from chilled iron or tungsten carbide for the heavier wires. The horse power necessary to draw the wire through the die is equivalent to the elastic limit of the wire, times the drawing speed in feet per minute, divided by 33,000. In wire finishing at a diameter of .192", the tension is approximately 2,100 pounds and the speed of drawing 400 feet per minute, representing actually 25.4 horse power, to which must be added machine friction and other losses in the efficiency of the drive.

In the preferred embodiment of the apparatus and the process of the present invention, the wire drawing is effected through a series of radially disposed rolls in two or more groups, each group having three or more sets of rolls, the axes of the rolls in each group coinciding on a single plane. To effect close spacing and to allow a better work distribution on the wire, the radial line of roll group positions is staggered to an intermediate overlapping relation. Ordinarily the first group preferably consists of four rolls, set at 90 degree positions and the second group at 90 degree positions, but rotated on the axis plane to 45 degrees from the first group position. In this arrangement the wire is first drawn to a square, and then to a round. In a combination where three rolls are used, in each group the wire is first drawn into a triangle and then into a round cross sectional area. Any number of rolls can be used in each group, the first forming flat faces and the second sizing the product to a round finish. The only limitation to the number of rolls used in each group is that of close nesting of the roll groups. This nesting is important for it has been found that if the groups are too far separated, the wire has a tendency to rotate slightly between the groups, resulting in a multisided or finned product, rather than the desired round wire.

Another feature of extreme importance is the diameter of the rolls. Large rolls over 6" in diameter create excessive roll bearing pressure, due to the greater area of contact on the wire, and they furthermore interfere with close nesting. It has been found that rolls in diameter between 3" and 5" permit adequate bearing design, depending of course on the diameter of the

wire drawn. They also considerably lessen the bearing load, and at the same time permit of a close arrangement of roll groups. This is desirable for economic and quality production.

In a power test, producing wire with the new apparatus and process, it has been found that on a wire having a finished diameter of .192", and operating at a speed of 540 feet per minute, 18.5 horsepower is sufficient, including losses in efficiency of drive and machine mechanism. This indicates at least 100 percent increase in efficiency in power alone over the existing method of drawing wire through dies. From a production standpoint, the machine is capable of producing this .192" diameter wire at a rate of 690 feet per minute. In this case, indicated horsepower figures will be 26. Such speed would be impracticable in the ordinary wire drawing die, due to the increased friction and consequent heating.

Physical tests of wire drawn by the apparatus and involving the new process indicate a structure not only comparable in every way with wire drawn by the old method, but having added physical advantages not possible heretofore. A microphotograph at 100 diameter magnification shows a homogeneous grain structure, neither distorted nor ruptured in the direction of drawing. From an examination of a micrograph showing the structure of ordinary cold drawn wire, it is evident that the grain structure is considerably elongated, due to the extreme tension in the drawing of the wire. Slips and longitudinal ruptures are also apparent. While this does not seriously affect the strength of the wire longitudinally, transversely the granular bond is almost ruined. This manifests itself physically if the wire is sharply bent, flattened or upset.

A form of apparatus that has proven efficient for securing the above and other desirable results is illustrated in the accompanying drawings, wherein:

Figure 1 is a plan view of the same.

Figure 2 is a perspective view of the drawing mechanism.

Figure 3 is a longitudinal sectional view through the same.

Figure 4 is a cross sectional view on the line 4—4 of Figure 3.

Figure 5 is a cross sectional view on the line 5—5 of Figure 3.

Figure 6 is a longitudinal sectional view on the line 6—6 of Figure 5.

Figure 7 is a detail view in elevation of the lubricant supply and atomizing means.

Figure 8 is a detail sectional view through an atomizer and on the line 8—8 of Figure 7.

5 Figure 9 is a detail view on an enlarged scale of the cooperating portions of one group or set of roller dies.

Figure 10 is a cross sectional view showing the form of the stock to be operated upon.

10 Figure 11 shows the form the stock takes under the operation of the first set of rolls.

Figure 12 is a cross sectional view of the final product.

Figure 13 is a diagrammatic view of a set of dies 15 for initially forming the stock into triangular shape.

Figure 14 is a cross sectional view of the stock as initially acted upon.

Figure 15 shows the stock when operated upon 20 by the initial set of rolls shown in Figure 13.

Figure 16 shows the form of the stock operated on by a second group of rolls.

25 Figure 17 shows the final product. These series of steps utilize four sets of rolls, as will be readily understood.

Figure 18 is a detail side elevation of the pulling and coil-forming mechanism.

Figure 19 is an end elevation of the same.

30 Figure 20 is a detail cross sectional view taken on the line 20—20 of Figure 19.

If reference is had to Figure 1, there is shown therein at 21, the mechanism by which the stock is reduced to the final product. The lubricating system for the drawing mechanism 21 is generally illustrated at 22. The pulling drum and 35 coil-forming mechanism is designated 23. As shown in this figure a motor 24 drives through belting 25, speed change mechanism 26 that may be of standard form. From this mechanism a 40 drive shaft 27 operates a clutch 28, through which is driven a shaft 29 operating the pulling and coil-forming mechanism 23. The clutch is operated from a conveniently located hand lever 30 having connections 31 with said clutch. As the driving 45 mechanism is made up of well-known instrumentalities and may be varied as desired, it is believed that the above description and the showing is sufficient for the purposes of explanation.

Referring now to the wire drawing mechanism 50 as illustrated in Figures 2—9 inclusive, a supporting structure is provided, consisting of a head 32 and a second head 33 spaced therefrom. These heads are provided with trunnions 34 and 35 seated in the upper ends of standards 36. 55 The trunnions are held in place by cap plates 37 and 38, respectively, secured to the standards 36 by bolts 39. When these bolts are tightened, the trunnions 34 and 35 are secured against rotation, but when the bolts 39 are loosened, the trunnions and consequently the heads and everything carried thereby can be rotated.

The said heads are provided with peripherally opening recesses 40, in which are seated the ends of carrier bars 41 that connect the said 65 heads and are held in place in the recesses by removable cap plates 42. It will be noted by reference to Figures 2 and 3 that the bars 41 are inwardly inclined toward the rear head 33, or in other words, converge toward said head. It 70 will also be noted by reference particularly to Figure 5 that alternate sets of bars are set closer to the axis of the heads than others, as indicated by the space "X" between the circles intersecting respectively the inner faces of said bars.

75 The head 32, which may be termed the "en-

trance" head because it is through that head that the stock enters, is provided with a central opening 43, and the trunnion 34 for said head is provided with a registering opening, the walls of which are threaded, as at 44. A guide spindle 45 5 is threaded into said trunnion 34 and projects through the opening 43 into the interior of the supporting structure. It can be secured in adjusted position by a lock nut 45a. Through this spindle the stock 46 enters the drawing mechanism. The opposite or "exit" head 33 and its trunnion 35 have an axial passageway 47 for the wire or finished product 46a.

Mounted on the carrier bars 41 are sets of carriages, two of these sets being shown in the 15 present embodiment, though a greater number may be employed, as desired. One set, which is located closer to the entrance head 32, is mounted on the outer of the bars 41, the other set, being located closer the exit head 33, is mounted on 20 the inner set of said bars. As the structures of the carriages are similar in all respects, a description of one will be sufficient for all. Each carriage is formed of side sections or plates 48 suitably reinforced with external ribs 49, the 25 outer ends of said plates embracing the bar 41 and being secured together by tie bolts 50, which serve to clamp the plates securely to the bar. However, upon loosening the bolts, obviously the plates or carriages can be moved longitudinally 30 along the bar. The inner end portions of the said plates are spaced apart a distance less than the thickness of the bars 41 and these inner portions are connected by an axle 51 having an enlarged bearing flange 52 interposed between said 35 plates. The axle thus serves as an effective tie and also as a spacing member for the plates. Surrounding the axle and located between the plates is a roller die element 53 which is thus 40 relatively thin and preferably has a tapered peripheral portion that acts upon the work. This die element has a roller bearing 54 on the enlarged portion 52 of the axle, as clearly shown in Figures 4 and 9. The die elements of each set are radially disposed and their innermost 45 portions meet or practically meet on opposite sides of the stock.

As clearly shown in Figures 2, 3 and 4, by having the two sets of carriages and their die elements alternated, and by reason of the structural character of the die mountings, the active portions of the roller die elements of one set are very closely associated with those of the other set, for the arrangement is such that the carriages and rollers of one set enter the spaces between 55 those of the other set, or in other words, they are in overlapping relation.

Considering the structure as thus far described therefore, it will be evident that when the stock passes through the same, the first set of rollers 60 will initially act thereupon, and directly adjacent to their plane of action, the second set, immediately following, will operate. Now if reference is had to Figures 10, 11 and 12, the initial stock is shown at 46 in Figure 10, and in the preferred 65 form of construction, the peripheral faces of the first set of dies are flat, so that the action of said dies results in the stock being deformed to angular flat faces, as shown in Figure 11. The second set of dies are peripherally grooved and thus 70 reduce the stock to the finished product 46a of Figure 12 in its round form. Additionally by having the two sets of die rollers in such close relation a serious difficulty has been overcome, in 75 that there is no tendency of the wire to twist 75

between the sets of dies, and consequently danger of the formation of fins, or otherwise deformed product is avoided. Furthermore it has been found that the wire produced has an unexpectedly high degree of conductivity, which the micro-photograph definitely seems to show is due to a peculiarly efficient homogeneous grain structure that is neither distorted nor ruptured in the direction of the drawing action. In connection with the action of the dies, as above explained, the directing spindle 45 is important, as it directs and supports the stock up to its point of contact with the first set of die rollers.

The adjustment of the carriages on the carrier bars is an important feature in that it readily permits, by the movement of the carriages along the bars, their being spaced different distances apart for operation on stock of different sizes and the production of products of different diameters. More than that, as the dies are worn they can be shifted along the carrier bars toward the exit head and thus their life may be greatly prolonged. In this latter connection, the structure of the supporting mechanism is important. As will be clear by reference to Figure 2, the mechanism is of a skeleton formation, so that everything is visible and available. More than that by detaching the proper cap pieces 42, any bar with the carriage and die assembly thereof can be easily removed and replaced. Furthermore though the supporting frame is normally held against rotation, by loosening the bolts 39 and the cap plates 37, the entire structure can be rotated, so that the lowermost bars can be brought to a position where they are available for such removal and replacement.

In order that the roller dies shall function properly and efficiently for extended periods, means are provided for both lubricating the same and preventing the entrance to the bearings of scale or other detritus.

Referring to Figures 3 and 6, the trunnion 35 of the exit head 33 is provided with a passageway 55 leading from the cap plate 38 therefore and opening into an annular manifold groove 56 formed in the head 33. From this groove branch conduits 57 are connected to ports in nipples 58 that fit into the receiving ends of passageways 59 formed in the carrier bars 41. These passageways 58 have outlet ports 60 in the inner sides of the bars 41, and one of the plates of each carriage has a channel 61 that is in communication with the port 60, irrespective of the adjustment of the carriage on the bar. This channel has a port or passageway 62 leading into the roller bearing.

Referring to Figures 1 and 7, a pipe 63 is provided leading from any suitable source of air under pressure, and this pipe is connected at 64 with the passageway 55 in the trunnion 35. A pressure reducing valve 65 of any suitable form may be located in the pipe 63, as is also a controlling valve 66. A lubricant reservoir 67 has an outlet 68 terminating in a nozzle 69 (see Figure 8) that drops oil into a reduced Venturi-like passageway 70 in the air conduit 63. The size of this passageway may be varied by a screw 71 transversely threaded into the structure and disposed oppositely to the outlet from the nozzle 69. Obviously this produces an atomizer for the oil. Pressure in the reservoir 67 is maintained by a branch pipe 72 leading from the air supply pipe 63, and coupled to the top of the reservoir.

With this structure, air laden with oil in atomized condition is carried through the pipe 63,

and the various conduits and passageways of the supporting structure to the bearings of the roller die elements and these are thus not only kept lubricated but by reason of the pressure in the bearing chambers, lubricant is carried along the sides of the rollers and the outward flow of air prevents the entrance of scale or other foreign material entering the bearings of the rollers.

In order to pull the material through the drawing dies and effect successful coiling of the finished product, the following mechanism is employed, particular reference being had to Figures 18, 19 and 20 for the detail structure thereof.

As already explained, this mechanism is designated generally by the reference numeral 23 and as shown in Figure 1 is driven by the shaft 29. The structure comprises an outwardly tapered winding drum 73 provided at its larger end with an outstanding peripheral flange 74, and having longitudinally disposed arms 75 projecting from its outer or smaller end. Surrounding this drum is a coil-forming and confining cage, consisting of end rings or hoops 76 and 77 connected by spaced bars 78. These rings or hoops constitute circular tracks that run on supporting rollers 79 so that the cage is rotatably supported independently of the drum 73. It will also be noted by reference to Figures 18 and 20 that the inner ring 76 terminates short of the flange 74, leaving an open space through which the finished product 46a can pass, and be wrapped upon the larger end of the drum 73. Plates 80, mounted on certain of the cage bars 78, support inwardly inclined spring arms 81, which terminate in flat shoes 82 adapted to rest on the wrapped product 46a. The free ends of these shoes are preferably overturned as shown at 83 and are spaced from the flange 74 of the drum.

The cage is rotated from the drum 73 by radial arms 84 pivotally mounted on the free ends of the drum arms 75 and engaging in keepers 85 carried by the outer cage ring 77. The arms 84 can be swung outwardly to positions in substantial alignment with the drum arms 75 and said arms 84 are held in either their outstanding positions, or in their connecting positions by springs 86 mounted on the arms 75 and bearing against the angular ends 87 of the arms 84.

The operation of this winding and coiling mechanism is substantially as follows: As the mechanism is rotated, the finished product or wire is initially wrapped on the larger end thereon, as illustrated at Figure 20, and as these wraps continue, they are forced in under the shoes 82, which hold them snugly upon the drum and thus secure sufficient frictional engagement to prevent slippage. In time these wraps, however, pass beyond the shoes 82 on to the outer portion of the drum and within the cage, where they can expand to form coils. When a sufficient number have accumulated, they may be tied into a bundle and by swinging the arms 84 outwardly, this bundle may be readily removed from the cage and drum.

With this structure therefore, it is found unnecessary to secure the end of the wire to the coiling and pulling mechanism thus allowing the coil to have free movement within the outside coil-confining cage or guard, and the spring action of the wire causes a compact and well formed coil to develop within the same, thus avoiding poorly produced coils very broad in width which are hard to handle and which in past practice usually have to be rewound.

While two sets of drawing rollers have been shown it will be evident that the number of 75

sets and the number of rolls in a set may be varied. Thus it is entirely possible to use three rolls in a set instead of four, as illustrated in Figure 4, and to increase the number of sets. This is shown, for example, in Figures 13-17 inclusive. In Figure 13 there is illustrated diagrammatically a set of three rolls 53a. Such sets may be arranged in tandem and interrelated exactly as shown in the first described embodiment. With such a structure four of the sets may, for example, be employed, and by referring to Figures 14-17 inclusive, the stock 46b is thereby reduced first to triangular relation, as shown at 46c in Figure 15 by the first set of rolls illustrated in Figure 13, 10 then to hexagonal formation by the second set, as shown at 46d in Figure 16, and finally into 15 the round product 46e of Figure 17.

From the foregoing, it is thought that the construction, operation and many advantages of the 20 herein described invention will be apparent to those skilled in the art without further description, and it will be understood that various changes in the size, shape, proportion and minor details of construction may be resorted to without departing from the spirit or sacrificing any 25 of the advantages of the invention.

What I claim, is:

1. In apparatus of the character described, the 30 combination with a supporting structure having means for admitting stock thereto and the exit of the altered product therefrom, of a plurality of carrier members extending longitudinally along and on different sides of the path of the stock in the supporting structure, said carrier members 35 being disposed in convergent relation, carriages movable longitudinally along the carrier members, and die elements mounted on and movable with the carriages, die elements being thereby movable to varied spaced relations, means for 40 fixing the carriages at different points on the carriers, and means for drawing stock between the die elements when fixed in their adjusted positions.

2. In apparatus of the character described, the 45 combination with a supporting structure having means for admitting stock thereto and the exit of the altered product therefrom, of a plurality of carrier members extending longitudinally along and on different sides of the path of the stock in the supporting structure, said carrier members 50 being disposed in convergent relation, carriages movable longitudinally along the carrier members, roller die elements journaled on the inner ends of the carriages and movable therewith, said 55 die elements being thereby movable to varied spaced relations, means for fixing the carriages at different points along the carriers, and means for drawing stock between the roller dies when the carriages are fixed.

60 3. In apparatus of the character set forth, the combination with a supporting structure comprising spaced heads having openings respectively for the entrance of the stock and the exit of the product of carrier bars connecting the heads and 65 converging toward the head having the exit, carriages mounted to slide longitudinally on the bars, roller dies journaled on the inner ends of the carriages and operating on different sides of the stock passing through the structure, said 70 roller dies moving toward or from each other when the carriages are adjusted along the bars, means for fixing the carriages at different points along the carriers, and means for drawing stock between the roller dies when the carriages are 75 fixed.

4. In apparatus of the character described, the combination with a supporting structure comprising spaced heads having openings respectively for the entrance of the stock and the exit of the product, of carrier bars connecting the heads and 5 having their ends removably mounted respectively on said heads, carriages mounted on the bars, and die elements mounted on the carriages and operating on different sides of the stock, passing through the supporting structure, each of said 10 carriages and die elements being removable in assembled relation when the bar carrying the same is removed from the heads.

5. In apparatus of the character described, the combination with a supporting structure comprising spaced heads having openings respectively for the entrance of the stock and the exit of the product, of carrier bars connecting the heads and 15 having their ends removably mounted respectively on said heads, said bars converging towards the 20 head through which the product exits, carriages movable along said bars, means for securing the carriages at different positions theron, and roller die elements journaled on the carriages and being moved different distances apart on the adjustment 25 of the carriages, each carriage and its die element being removable with the bar carrying the same.

6. In apparatus of the character described, the combination with a supporting structure including spaced heads having respectively provision for the entrance and exit of the work, of sets of carriers connecting the heads, those of one set being located at different distances from the path of the work than those of another set, a set of carriages 30 on each set of carriers, and a set of die elements 35 on each set of carriages, said sets of die elements being located in tandem relation.

7. In apparatus of the character described, the combination with a supporting structure including spaced heads having respectively provision for the entrance and exit of the work, of sets of carrier bars connecting the heads on different sides of the path of the work, said bars converging toward the exit of the work and those 45 of one set being located closer to the path of the work than those of the other set, a set of carriages mounted on each set of bars and adjustable along the same, and a set of roller die elements journaled on each set of carriages and 50 adjustable therewith, the roller die elements of one set being arranged in tandem relation to those of the adjacent set.

8. In apparatus of the character described, the combination with a supporting structure including spaced heads having respectively provision for the entrance and exit of the work, of sets of carrier bars connecting the heads on different sides of the path of the work, said bars converging toward the exit of the work and those 60 of one set being located closer to the path of the work than those of the other set, a set of carriages mounted on each set of bars and adjustable along the same, and a set of roller die elements journaled on each set of carriages and 65 adjustable therewith, the roller die elements of one set being arranged in tandem relation to those of the adjacent set, and those of one set overlapping and being interposed between those of the adjacent set.

9. In apparatus of the character described, the combination with spaced standards, of heads having trunnions journaled in the standards and provided with passageways for the work, means for normally holding the heads against 70

rotation, convergently disposed carrier bars connecting the heads, carriages slideable on bars and having means for clamping the same to hold the carriages against movement and in different positions, roller dies journaled on the carriages and operating on different sides of the work passing through the trunnions, said carriages and dies being disposed in sets and the dies of the different sets being located in interposed overlapping relation, and means for detachably securing the bars to the heads.

10. In apparatus of the character described, the combination with a supporting structure, of roller dies journaled therein, mountings for said dies, a source of lubricant, means for conducting lubricant to the die mountings and to the die journal bearings, and means for atomizing the lubricant and delivering it under pressure to the conducting means and thence to the die journal bearings.

11. In apparatus of the character described, the combination with a supporting structure comprising spaced heads, of carriers connecting the heads, carriages mounted on the carriers, roller dies journaled on the carriages, lubricant conducting conduits extending through the carriers and carriages to the roller die journals, and means for supplying lubricant to said conduits.

12. In apparatus of the character described, the combination with a supporting structure comprising spaced heads, of carriers connecting the heads, carriages mounted on the carriers, roller dies journaled on the carriages, conduits in the carriages leading to the journal bearings of the dies, a supply passageway in the head in communication with the conduits, and means for atomizing lubricant under air pressure and delivering lubricant in the air under pressure to said passageway and thence to the journal bearings.

13. In apparatus of the character described, the combination with a supporting structure comprising spaced heads and carrier bars connecting the heads, of carriages on the bars and roller dies journaled on the carriages, a manifold in one head, passageways in communication with the manifold and extending through the carrier bars and carriages to the roller die journals, and means for supplying lubricant under pressure to the manifold.

14. In apparatus of the character described, the combination with a supporting structure comprising spaced heads and carrier bars connecting the heads, of carriages on the bars and roller dies journaled on the carriages, a manifold in one head, passageways in communication with the manifold and extending through the carrier bars and carriages to the roller die journals, means for supplying lubricant under pressure to the manifold, and means for atomizing the lubricant prior to its entrance into the manifold.

15. In apparatus of the character described, the combination with a supporting structure comprising spaced heads and carrier bars connecting the heads, of carriages adjustably mounted on the bars and roller dies journaled on the carriages, a manifold in one head, passageways in communication with the manifold and opening through the sides of the carrier bars, passageways in the carriages communicating with the journals of the roller dies, said passageways of the bars and carriages being in communication and maintaining such communication on the ad-

justment of the carriages, and means for supplying lubricant under pressure to the manifold.

16. In apparatus of the character described, the combination with a supporting structure comprising spaced heads and carrier bars connecting said heads, of carriages mounted on the bars and comprising wall sections that embrace and are clamped to the bars and project inwardly therefrom, said inwardly projecting parts having portions spaced apart, and roller die disks 10 rotatably mounted between the latter portions.

17. In apparatus of the character described, the combination with a supporting structure comprising spaced heads and carrier bars connecting said heads, of carriages mounted on the bars and comprising wall sections that embrace and are clamped to the bars and project inwardly therefrom, said inwardly projecting parts having portions spaced apart, axles connecting said latter portions, roller die disks located between the portions, roller bearings between the disks and axles, and means for supplying lubricant under pressure to said bearings, and causing an outward pressure alongside the disks.

18. In apparatus for drawing wire and the like, the combination with sets of freely and individually rotating coacting dies, said sets being arranged in tandem relation and each set individually acting on the stock passing through it to reduce and elongate the same, the rotatable dies of one set being disposed in overlapping relation to those of the adjacent set, means for mounting the sets and causing their relative adjustment towards and from each other, and means at the discharge side of the sets of dies 35 for drawing the finished product through the sets of dies and pulling the untreated stock into the same.

19. In apparatus for drawing wire and the like, the combination with sets of freely and individually rotating coacting dies, said sets being arranged in tandem relation and each set individually acting on the stock passing through it to reduce and elongate the same, the rotatable dies of one set being disposed in overlapping relation to those of the adjacent set, means on which the sets are rotatably mounted, said means being adjustable longitudinally of the path of travel of the work operated on by them, said adjustment causing the movement of the dies of each set 50 towards each other, and means at the discharge side of the sets of dies for drawing the finished product through the sets of dies and pulling the untreated stock into the same.

20. In apparatus for drawing wire and the like, the combination with sets of freely and individually rotating coacting dies, said sets being arranged in tandem relation and each set individually acting on the stock passing through it to reduce and elongate the same, the rotatable dies of one set being disposed in overlapping relation to those of the adjacent set, means on which the sets are rotatably mounted, said means being longitudinally adjustable of the path of travel of the work operated on by them, said adjustment causing the movement of the dies of each set towards each other, means for directing the stock to the first set of dies, said means being also adjustable longitudinally of the path of travel of the work, and means at the discharge side of the sets of dies 70 for drawing the finished product through the sets of dies and pulling the untreated stock into the same.

21. In apparatus for drawing wire and the like, the combination with supporting means, of draw- 75

- ing die rolls having journal bearings in the supporting means, passageways leading to said bearings, and means for atomizing lubricant in air under pressure and delivering said air under pressure with the atomized lubricant through the various passageways to lubricate the said bearings and create outward pressure of air in the bearings to prevent the entrance of detritus thereto.
- 10 22. In apparatus for drawing wire and the like, the combination with supporting means, of drawing die-rolls having journal bearings on the supporting means, passageways leading to said bearings, a manifold having connections with the various passageways, and means for atomizing lubricant in air under pressure and delivering said air under pressure combined with the atomized lubricant through the manifold and thence into the various passageways to the said bearings to lubricate the same and create outward air pressure in the bearings to prevent the entrance of detritus thereto.
- 15 23. In apparatus of the character described,

the combination with a supporting structure having means for admitting stock thereto and permitting the exit of the altered product therefrom, of a plurality of sets of coating relatively rotatable die elements that respectively operate on different sides of the stock for altering the same, means on which the die elements of each set are adjustably mounted, and by which they are movable to different positions along the path of travel of the stock, said means also adjusting distance 10 of the dies from the path of the stock.

24. In apparatus of the character described, the combination with spaced heads through which the stock and finished product passes, means connecting the heads, die carriers on said means 15 operating on different sides of the stock, said heads, connections and dies being rotatable about the path of the stock to bring the different dies into accessible position, and means for normally holding the heads against rotation when the dies 20 are operating on the stock.

WALTER F. SCHULZ.
